[57] CLAIM

The ornamental design for an illuminated cab sign, as shown and described.

DESCRIPTION

FIG. 1 is a front perspective view thereof;
FIG. 2 is a top plan view thereof;
FIG. 3 is side elevation view thereof;
FIG. 4 is a bottom plan view thereof;
FIG. 5 is back elevation view thereof;
FIG. 6 is a front elevation view thereof; and,
FIG. 7 is a side elevational view of a second embodiment
thereof, wherein the only difference resides in the display
panels at the bottom portion.
